UNITED STATES PATENT OFFICE.

WALTER H. LIVINGOOD, OF BERKELEY, CALIFORNIA.

PISTON FOR INTERNAL-COMBUSTION ENGINES.

Application filed September 8, 1922. Serial No. 587,030.

To all whom it may concern:

Be it known that I, WALTER H. LIVINGOOD, a citizen of the United States, residing at Berkeley, in the county of Alameda and 5 State of California, have invented new and useful Improvements in Pistons for Internal-Combustion Engines, of which the following is a specification.

This invention relates to pistons for internal combustion engines, the primary object being to provide a novel structure of a piston by the use of which the renewal of the upper piston ring or rings may be readily effected.

10 15 A further object of this invention is to provide a piston of simple design such as will ensure an extremely lightweight structure.

A still further object of this invention is 20 the provision of a sectionally constructed piston particularly adapted for internal combustion motors which provides means for effectively locking the cap or upper portion of a sectional piston structure, means for 25 preventing the lateral displacement of the wrist pin, and a series of ports or openings in the walls thereof whereby lightness in weight is ensured.

With the foregoing and other objects in 30 view as will be later on more apparent, my invention consists essentially in the novel features of construction, combination and arrangement of parts hereinafter particularly described and more specifically defined 35 by the appended claims.

In the further disclosure of the invention reference is to be had to the accompanying sheets of explanatory drawings constituting a part of this specification and in which like 40 characters of reference designate the same or corresponding parts in all the views.

Figure 1—is a side elevation of a sectional piston for internal combustion engines as embodying my invention.

45 Figure 2—is a central longitudinal section through the same.

Figure 3—is a cross section taken substantially on the line 3—3 in Figure 1, and looking in the direction of the arrows.

50 Figure 4—is a cross section taken substantially on the line 4—4 in Figure 1 and looking in the direction of the arrows.

Figure 5—is a central longitudinal section through a modified form of the invention; 55 and,

Figure 6—is a cross section taken substantially on the line 5—5 in Figure 5, and looking in the direction of the arrows.

Referring more particularly to the drawings the numeral 10 indicates the main or body portion of the piston and 11 the screw cap thereof which may be readily removed for the replacing of a worn ring and again replaced by applying an appropriate tool to the rectangular slot 12 which is provided in 60 the top face of said screw cap 11, said screw cap 11 being also internally threaded and adapted to register with a corresponding thread 13 on the shouldered portion 14 of the main piston portion 10.

70 In securing the screw cap 11 on the body portion 10 the top groove 15 adapted for the reception of a piston ring is formed by the extending flanges 16 and 17. Directly below the flange 17 on the piston portion 10 75 are four or more projecting lugs 18 which act as guides or supports for a suitable packing, such as asbestos cord packing which is wound about the body portion intervening 80 the lugs 18 and the flange 17 as indicated by the dotted lines 19 in Figures 1 and 3, said packing 19 being intended to prevent an undue amount of oil from working its way into the combustion area, or past the first piston ring.

85 Peripherally central with the wrist pin 20 is an extra large or main piston ring 21 which encloses the apertures 22, provided for the wrist pin 20 and prevents any lateral displacement of said wrist pin 20.

90 The undercut portion 23, 24 immediately above and below the main ring 21 is substantially of a T section 25 with a series of apertures or openings 26, permitting ample cylinder wall lubrication and reducing the 95 weight of the piston to a minimum.

100 Referring more particularly to the locking means for preventing the annular screw cap or cover 11 from working loose while in operation, I drill through the cap 11 and part way into the peripheral face of the shoulder portion 14 and thread the aperture thus formed in screw cap 11 and shoulder portion to receive threaded locking pin 27, or alternatively I may employ the locking 105 means illustrated in Figures 5 and 6. The locking means shown by Figures 5 and 6 consist of a locking spring ring or member 28, adapted to seat in an annular groove 29 located on the inner periphery of the an-

nular screw cap 11, said groove 29 being provided with an inwardly projecting stop 30 which provides abutting means for the aforesaid locking spring ring or band member 28, which is provided with an inwardly bent extending portion or tongue 31 for engagement in the notches or teeth 32 formed on a co-operating locking member 33 consisting of a flat metal strip which is corrugated or formed with a plurality of teeth or notches 32, said metal strip or locking member 33 being adapted to seat in a groove or slot 34 provided for the same. This co-operating locking member 33 is rigidly secured 10 in the slot or groove 34 by inserting the free ends 35 thereof through an aperture or slot 36 at right angles with the groove or slot 34, said free ends 35 extending through said aperture or slot 36 and being turned over 20 or clinched on the face of the inner periphery of the main piston body portion 10.

From the foregoing description it will be apparent that when a renewal of the upper or top piston ring or rings is desired, it is only necessary to remove the uppermost portion or screw cap 11, leaving the lower or main portion of the piston 10 intact on the connecting rod of an internal combustion motor and it will be observed that my novel 25 sectional piston structure is provided with internal locking means preventing the upper and lower sections which are inter-connected by a screw thread from working loose or turning on the screw thread.

30 While there has been shown and described a preferred embodiment of my invention, it is to be understood that my invention is susceptible of various changes in the details of construction and the right is 35 hereby reserved to make such modifications

as fairly fall within the scope of the appended claims.

Having described my invention, what I claim as new and desire to secure by Letters Patent, is:

45 1. In a piston for internal combustion engines the combination of a main body portion having diametrically opposed elongated peripheral apertures in reduced parts of the wall thereof, a grooved medial portion for the reception of a piston ring, journals in the medial portion for a wrist-pin the outer ends whereof are closed in by the piston ring, 50 outset lugs for supporting the packing ring in spaced relation relative to the piston ring, a removable cap for the piston, and means for locking said cap securely on the body portion.

55 2. In a piston for internal combustion engines the combination of a main body portion having diametrically opposed elongated peripheral apertures in reduced parts of the wall thereof, a grooved medial portion for the reception of a piston ring, journals in the medial portion for a wrist-pin the outer ends 60 whereof are closed in by the piston ring, outset lugs and an annular flange near the head of the piston for supporting a packing ring in spaced relation relative to the piston ring, a removable cap for the piston, and 65 means for locking said cap securely on the body portion.

70 In testimony whereof I affix my signature.
